UNITED STATES PATENT OFFICE.

JOHN GEO. LUDWIG, JR., OF FREELAND, PENNSYLVANIA.

ADJUSTABLE SECTIONAL BEARING.

1,109,773.

Specification of Letters Patent.

Patented Sept. 8, 1914.

Application filed June 2, 1913. Serial No. 771,254.

To all whom it may concern:

Be it known that I, JOHN GEORGE LUDWIG, Jr., a citizen of the United States, residing at Freeland, in the county of Luzerne 5 and State of Pennsylvania, have invented certain new and useful Improvements in Adjustable Sectional Bearings, of which the following is a specification, reference being had therein to the accompanying drawing.

10 This invention relates to a bearing, and the principal object of the invention is to provide a bearing which is adjustably mounted so that the bearing block may be moved transversely to assume the proper position.

15 Another object of the invention is to provide an improved means for mounting the bearing block so that the adjustment will be permitted.

20 With these and other objects in view, this invention consists of certain novel combinations, constructions and arrangements of parts as will be hereinafter fully described and claimed.

25 This invention is illustrated in the accompanying drawing, wherein:

Figure 1 is a side elevation of the improved bearing. Fig. 2 is a top plan view of the bearing. Fig. 3 is an end elevation 30 of the improved bearing. Fig. 4 is a side view of the bearing block showing the grooves in which the set screws fit.

This invention comprises a frame in which the bearing block is adjustably mounted and 35 the cap adjustably connected with the frame and positioned above the bearing block. The frame comprises a base plate 10 from which the converging walls 11 extend. These walls 11 are provided with enlarged 40 upper end portions 12 which form supports for the cap 13 and which carry the threaded pins 14. These pins 14 extend through elongated openings 15 formed in the cap 13 and carry securing nuts 16 which hold the cap 45 in an adjusted position. Set-screws 17 pass through openings in the upper end portions of the side walls 11 into the grooves 18 of the bearing block 18 so that the bearing block may be held in an adjusted position. 50 Jam-nuts 19 are carried by the set-screws

so that the set-screws will be held in a desired position. This bearing block 18 is tapered as shown in Fig. 1, and is slidably mounted upon the base plate 10 between the walls 11 and beneath the arched central portion of the cap 13. The upper face 20 of the bearing block is curved as shown in Fig. 1 so that a shaft may be rotatably supported by the bearing block. An I-bolt 21 is carried by the block 18 so that the block may be 60 easily withdrawn from between the walls 11 when desired. When this device is in use, the base-plate 10 is secured in place by suitable bolts passing through the openings 22 and the bearing block 18 is then put in place 65 with the shaft resting in the curved upper face of the block. The set-screws 17 are then adjusted to bring the block in the desired position and after the jam-nuts 19 are tightened, the cap 13 is then put in place 70 and secured by the nuts 16. Openings 23 are provided so that oil may be fed to the shaft, thus causing it to turn easily in the bearing. By this arrangement, the bearing block can be adjusted without it being necessary to remove the base-plate, and therefore, 75 the same bearing may be used for a new shaft of different size from the old one, without it being necessary to remove the base-plate. It is, of course, obvious that 80 when the bearing block is moved the cap must also be adjusted.

What I claim, is:

A bearing comprising a base having upstanding integral side walls, threaded pins 85 carried by the upper ends of said walls, a bearing block positioned between said walls, said bearing block capable of longitudinal movement upon said base between said walls since the sides of said block are normally 90 spaced at a distance from said walls, said bearing block provided with vertical grooves upon its sides, set-screws passing through said side walls and positioned within said groove so as to engage the sides of said bearing block, said set-screws adapted to shift said block for adjusting the same, said 95 grooves bracing the inner ends of said screws, said bearing block provided upon its upper side with a shaft receiving pocket, a 100

cap carried upon the upper ends of said walls, said caps provided with longitudinal slots, said threaded pins adapted to pass through said slots, retaining means carried by said pins for holding said cap upon said walls, said cap also provided with a shaft receiving portion, said pockets adapted to receive a shaft whereby said block will move

the shaft and said cap will also be moved by the shaft.

10

In testimony whereof I hereunto affix my signature in presence of two witnesses.

JOHN GEO. LUDWIG, Jr.
